DESIGN FOR A SWEATER

Hans Boepple, New York, N. Y.

Application August 20, 1938, Serial No. 79,457

Term of patent 3½ years

To all whom it may concern:

Be it known that I, Hans Boepple, a citizen of the United States of America, residing in New York city, in the Borough of Manhattan, county and State of New York, have invented a new, original, and ornamental Design for a Sweater, of which the following is a specification, reference being had to the accompanying drawing, forming part thereof, wherein

I claim:

The ornamental design for a sweater, substantially as shown.

HANS BOEPPLE.
